(57) CLAIM

The ornamental design for a golf ball, as shown and described.

DESCRIPTION

FIG. 1 is a front elevation view of a golf ball showing the new design.

FIG. 2 is a rear elevation view thereof.

FIG. 3 is a left side elevation view thereof.

FIG. 4 is a right side elevation view thereof.

FIG. 5 is a top plan view thereof; and,

FIG. 6 is a bottom plan view thereof.

The word "SPEEDSOFT" shown in the figures is a registered trademark of Taylor Made Golf Company, Inc. and forms part of the claimed design.

The broken lines depict features of the golf ball that form no part of the claimed design.
